UNITED STATES PATENT OFFICE

95,001

DESIGN FOR AN OVERALL

Lawson W. Turner, Lynchburg, Va., assignor to
N. & W. Overall Company, Incorporated,
Lynchburg, Va.

Application January 4, 1935, Serial No. 54,719

Term of patent 14 years

To all whom it may concern:

Be it known that I, Lawson W. Turner, a citizen of the United States, residing at Lynchburg, in the county of Campbell and State of Virginia, have invented a new, original, and ornamental Design for an Overall, of which the following is a specification, reference being had to the accompanying drawing, forming part thereof.

Figure 1 is a rear elevational view of a pair of overalls constructed in accordance with the principles of the present inventive conception

and depicting in particular the dress type back rendered distinctive by the incorporation therein of a patch type reinforcement ornamental outline in configuration. The front of the overalls is conventional.

Figure 2 is a detail elevational view exaggerating in pictorial effect the yoke.

I claim:—

The ornamental design for an overall, as shown and described.

LAWSON W. TURNER.
